WILLIAM J. PHILBIN, OF SCRANTON, PENNSYLVANIA.

LIQUID-SOAP-DISPENSING DEVICE.

1,285,362.

Specification of Letters Patent. Patented Nov. 19, 1912

Application filed March 2, 1912. Serial No. 229,919.

To all whom it may concern:

Be it known that I, WILLIAM J. PHILBIN, a citizen of the United States, residing at Scranton, in the county of Lackawanna and State of Pennsylvania, have invented certain new and useful Improvements in Liquid-Soap-Dispensing Devices, of which the following is a specification.

This invention relates generally to liquid dispensers, and is adapted particularly to be used in dispensing liquid soap.

The primary object of this invention is to provide a device of the character mentioned for use around or adjacent wash stands, for containing liquid soap to be used in washing operations, and is featured by the lack of complicated mechanism for controlling the flow of the soap from the container.

A further object of the invention is to provide an improved liquid soap dispenser which is devoid of valves or other devices for opening or closing the communication between the dispensing nozzle and the receptacle for the liquid.

A still further object of the invention is to provide an apparatus of the character stated which may be easily and quickly operated to deliver the liquid from the reservoir, which operates in such manner as to deliver only a specific small quantity of the liquid at one operation, which is capable of being manufactured and installed at exceedingly low cost, which is composed of but very few simple and readily assembled parts, and which will prove highly practical and efficient in use.

With these objects in view, together with others which will appear as the description proceeds, the invention resides in the novel formation, combination, and arrangement of parts, all as will be described more fully hereinafter, illustrated in the drawings, and particularly pointed out in the claims.

In the drawings:

Figure 1 is an end elevation of a dispensing apparatus constructed in accordance with the invention, the dotted lines indicating the position the reservoir and nozzle will assume when the device has been turned to dispensing position, and

Fig. 2 is a side elevation, parts in section, of the improved dispensing apparatus.

Referring now more particularly to the drawings, 3 indicates the shank or stem of the improved dispensing apparatus, the said shank being relatively small and may be con-

structed of metal or any other suitable material. The shank or stem has formed integral therewith at one end a cap indicated at 4, the said cap being disposed at right angles to the shank. One end of this cap is reduced and provides a nozzle 5, while the opposite end of the cap is internally threaded as at 6 to receive the externally threaded neck 7 of a container or reservoir indicated at 8. This container may be formed of glass, and is adapted to hold the liquid soap to be dispensed.

To control the flow of liquid from the reservoir to the nozzle, a diaphragm 9 is interposed between the neck of the bottle and the said nozzle. This diaphragm is of a diameter substantially equal to the interior diameter of the threaded portion of the cap, and is adapted, when in proper position to rest against the shoulders 10 within the cap. A washer 11 is interposed between the diaphragm 9 and the upper edges of the bottle neck, and it is obvious that when the bottle is screwed tightly into the socket end of the cap, the diaphragm will be forced into tight engagement at its edges with the shoulders 10, and the washer 11 will be tightly forced against the lower end of the said diaphragm. The diaphragm is provided with a relatively small central aperture 12 through which liquid passes from the receptacle to the dispensing nozzle.

The opposite end of the shank of stem 3 is provided with an annular channel 13, within which engages the inner end of a screw 14 threaded through the wall of a supporting socket 15. This socket is to be secured to the wall in a place convenient to the user of the dispensing apparatus, and it is obvious that when the stem end 3 is inserted in the socket and the screw 14 engaged in the annular recess 13 in the stem, the latter will be held against becoming detached from the socket and yet will be permitted to freely rotate.

In use, the bottle 8 is filled with the soap to be dispensed, and the neck 7 thereof is screwed properly in the socket end 6 of the cap. It will be understood that the diaphragm and washer will be assembled within the cap in the manner shown in Fig. 2. The weight of the bottle and its contents will hold the dispensing apparatus in inoperative position, as shown by the full line views in the drawing. When it is desired to dispense the liquid, it is but necessary to invert

the bottle, whereupon a quantity of liquid will flow through the central aperture 12 in the diaphragm 9 and will be discharged through the nozzle 5. Immediately upon release of the bottle or the nozzle, the device will assume inoperative or upright position. By reason of the fact that air can only be admitted to the interior of the bottle through the central aperture 12 in the diaphragm, only limited quantities of soap may be dispensed at each reversal of the position of the container, and the soap will thus be greatly economized.

From the foregoing it is obvious that I have provided an apparatus for dispensing soap which is of extremely simple construction but will operate properly for carrying out the desired end. For reason of the fact that the parts are readily separable, and when disconnected all the parts are easily accessible, the device may at all times be maintained in a sanitary condition. The dispensing apparatus may be equipped diaphragms having one or more openings for discharging the soap, as it may be desired to have a greater quantity of soap flow from the container than would be possible with a single small aperture in the diaphragm.

While the present is a disclosure of what is believed to be the preferred embodiment of the invention, it is to be understood that the invention is not limited thereto, but that various changes in the minor details of construction, proportion, and arrangement of

parts may be resorted to if desired without departing from the spirit of the invention as defined by the appended claims.

I claim:

1. In a device of the class described, a rotatable stem, a hollow cap at one end of said stem, shoulders projecting into the interior bore of said cap, means at one end of said cap for securing the neck of a container thereto, a perforate diaphragm smooth on both sides extending across the bore of said cap and resting against said shoulders, a washer interposed between said diaphragm and the neck of the container, and a nozzle at the opposite end of said cap.

2. In a device of the class described, a rotatable stem, a hollow cap at one end of said stem, shoulders projecting into the interior bore of said cap, means at one end of said cap for attaching the neck of a container thereto, a diaphragm smooth on both sides interposed between the neck of said container and said shoulders and resting against said shoulders, a nozzle at the opposite end of said cap, and said diaphragm having a central opening therein aligned with the opening in said nozzle and of smaller diameter than the latter.

In testimony whereof I affix my signature in presence of two witnesses.

WILLIAM J. PHILBIN.
